UNITED STATES PATENT OFFICE.

HENRY DRESES, OF CINCINNATI, OHIO.

CHANGEABLE-SPEED GEAR.

SPECIFICATION forming part of Letters Patent No. 773,005, dated October 25, 1904.

Application filed May 16, 1904. Serial No. 208,266. (No model.)

To all whom it may concern:

Be it known that I, HENRY DRESES, a citizen of the United States, residing in the city of Cincinnati, in the county of Hamilton and 5 State of Ohio, have invented certain new and useful Improvements in Changeable-Speed Gears; and I do declare the following to be a clear, full, and exact description thereof, attention being called to the accompanying two 10 sheets of drawings, with the reference characters marked thereon, which form also a part of this specification.

This invention relates to improvements in changeable-speed gear, being a device whereby, in a machine-tool, for instance, the speed by which the power is transmitted to it may be varied. These devices are therefore placed in an intermediate position between such machine-tool and the source of power for driving 15 it, which is usually a line or counter shaft.

The invention consists of certain features of construction whereby certain objections now inherent in such devices are removed. One of these objections is liability to injury 25 of the machinery, breakage, and stripping off of teeth when changing abruptly from a slower to a higher speed, and all of which is avoided by my improved construction, which further is of such a character as to permit 30 prompt adjustment by means of convenient manipulation and engagement of the parts only when in proper working position.

In the following specification, and particularly pointed out in the claims, is found a full 35 description of the invention, together with its operation and manipulation, parts, and construction, which latter is also illustrated in the accompanying two sheets of drawings, in which—

40 Figure 1 is a top view of the device with parts broken away and others in section. Fig. 2 is a front view of it, parts of the general frame being broken away and other parts being also shown in section. Fig. 3 is an end view of the device and as shown in the preceding figures. Figs. 4 and 5 show the driving-pulley of the device in sectional view and as these views appear if a section is taken on line 44 of Fig. 1. Fig. 6 is a side view of the

driven one of the first set of gear-wheels, being the slowest gear-train, and as such wheel appears if a section is taken on line 66 of Fig. 1. Fig. 7 is a vertical cross-section of the preceding figure, both being enlarged. Fig. 8 in a view similar to the corresponding parts 55 as they appear in Fig. 1 shows a modified construction of these parts, they constituting the means whereby the motion of the device is delivered to the machine to be operated.

In the drawings, 10 indicates the driving-shaft of the device receiving motion from a suitable source of power obtained from a motor direct or through the intervention of a line or counter shaft. 11 is the pulley which drives this shaft, and 12 is its loose mate, 65 upon which the belt is shifted when the device is not used.

13 is the driven shaft, it being also the shaft which is operatively connected to the machine or machine-tool driven by this device.

For the purpose of transmitting the motion from the drive-shaft to the driven one there are sets of gear-trains each consisting of two wheels mounted on these shafts, the faces of the complementary gear-wheels being opposite each other, but not in mesh, and their diameters being graduated in the usual manner to obtain different speeds and as best seen in the drawings. The two wheels of a set are engaged so as to operate by means of an idler 75 14, which simultaneously engages the two and which is supported so as to be adjustable laterally across the faces of all the wheels and capable of engaging any set of them, so that, each of the sets transmitting a different speed, 80 the adjustment of such idler and engagement by it of any particular set permits any of the available speeds to be transmitted to the driven shaft and by it to the machine to be operated.

For purposes of so manipulating the idler the same is mounted on a hand-lever 15, at one end of which there is a bearing 16, by which it is mounted on a guide-rod 17 and on which this lever, with the idler, may be laterally adjusted to meet any of the sets of gear-wheels, the manipulation being a lifting of the hand-lever, movement of it laterally, and dropping

of it when in the proper position so as to simultaneously engage the two gear-wheels of a set.

Since the points where the idler engages 5 the various sets of gear-wheels are not in a line parallel to rod 17 or to the shafts, it is also necessary that the pivot of lever 15 be a movable one, so that the idler meet the particular point of engagement. For such purpose this rod is supported on arms 18, one at each end, which arms are again pivotally attached to the general frame or housing of the device. By these means the idler may be moved to meet all positions for engaging any 15 of the sets of gear-wheels. In shifting the idler it is essential that the new position may be quickly found without unnecessary movements and be at once secured and held. This means that the idler should not be lifted higher 20 than necessary, yet at the same time sufficiently high to clear the intermediate sets of wheels over which it is passed to prevent striking them, which since they are in motion would be especially objectionable.

25 To prevent lifting higher than necessary, I provide a stop 19 on the under side of the hand-lever, which limits its lift when coming in contact with the under side of a shelf or ledge 20, upon which the lever normally rests 30 and which shelf projects from the frame of the device. To compel sufficient lift to prevent the idler from scraping against intermediate gear-wheels while adjusted laterally, there is a projection or pin 22 on the under 35 side of the hand-lever which when this latter is raised to proper height and shifted laterally prevents by its contact with shelf 20 lowering of the hand-lever in improper position except said pin has arrived over one of a number 40 of openings 23 in said shelf, one for each set of wheels, in which case only the hand-lever may be dropped sufficiently to effect working engagement—that is, mesh of the idler with both wheels of the particular gear-train. When in such proper position, the 45 idler is also locked by means of a spring-actuated locking-bolt 24, adapted to engage one of a number of openings 25 in the front side of shelf 20 and manipulated in a manner usual 50 with such devices. These openings 25 are so located that this locking is only possible when the idler is in proper position, as determined by pin 22 in conjunction with openings 23, the engagement of these openings 55 by pin 22 and bolt 24 being a simultaneous one.

To facilitate the manipulation and adjustment of the hand-lever, particularly its lateral shift, there are two additional handles 26, 60 both or either one of which may be used in conjunction with the handle on the lever. A groove 21 in shelf 20 serves as a guide in this lateral adjustment, pin 22 moving in it and never leaving it even after raised from openings 23, which latter are in the bottom of said

groove. Thus the idler while being adjusted laterally is confined to move in a line above the points of meshing contacts, so that when dropped it will drop in proper position only and requires never any transverse adjustment 70 to find a point of contact. I also make provision to overcome by means of an easy transition the high resistance momentarily created to prevailing driving power when changing to a faster speed to lessen as much as possible the objectionable effects of sudden jars and impacts, thus avoiding injury to machinery by breakage of teeth or otherwise. This occurs when the faster-rotating drive-shaft encounters the resistance due to the inertia of the stationary or slower-moving machinery or, what is the same, when this latter receives the sudden impetus of the faster motion. As to one of these provisions, I arrange that the driven shaft is always rotated at the slowest speed, 75 so that in case any higher speed is to be used the resistance which the drive-shaft encounters is lessened to an extent equal to the difference between machinery at a standstill and machinery in motion, or, in other words, 80 when starting work at a higher speed the start is not made with machinery at a dead stop, but with machinery in motion. This continual rotation at slowest speed refers of course only to such times when possibility of 85 using the particular machine-tool exists; otherwise loose pulley 12 would carry the belt or even this latter would be entirely at rest. This continual motion might be effected in this way: that the idler-wheel after every action 90 with a faster gear-train is shifted back to the slowest gear-train, which arrangement being left to the operator is, however, not altogether satisfactory and not as reliable as a permanent arrangement which is continually operative without requiring adjustment or attention. For such purpose I provide a stationary idler 27, which is continually in mesh with the slowest gear-train and always ready 95 to transmit motion from one shaft to the other. (See also Fig. 6.) The adjustable idler 14 is therefore not needed to operate this slowest gear-train, and to prevent all possibility of the former being thrown into gear I omit in front of this gear-train the opening 100 105 23, which would be necessary to receive pin 22 in order to permit the hand-lever, with this idler, to be lowered into mesh. To prevent interference by this permanent gear engagement with any of the other faster gear engagements whenever they are established, this first or largest gear-wheel on the driven shaft (indicated at 28) is loosely mounted and provided with a recess in its side which contains a ratchet-wheel 29, rigidly mounted 110 and to which the motion of wheel 28 is transmitted by means of pawls 31, kept in engagement by means of springs, as shown in Fig. 6. The action is a pushing one—that is, the 115 ends of the pawls push against the teeth of 120 125 130 135

the ratchet-wheel. When now any of the faster gear-trains is thrown into operation, causing the drive-shaft to rotate faster, this ratchet-wheel will simply move ahead and 5 away from the pawls, these latter slipping over the teeth and no interference results. The driven shaft rotates at the faster speed, and while the slower gear 28 rotates also it 10 transmits no motion. All the other gears on shafts 10 and 13 are rigidly mounted in the usual manner. Another and second means to ease this momentary resistance by a retarded transition from a slower to a higher speed is by 15 yieldingly mounting the driving-pulley 11 on shaft 10. For such purpose this drive-pulley is loosely mounted and has also a recess in its side which is occupied by a rigidly-mounted disk 32. This disk fills this recess, with the exception of an annular recess or space around 20 its edge, which, with the adjacent inner surface of the pulley, forms a spring-housing 33, which is occupied by a spring 34. One end of this spring bears against a plug 35, projecting from disk 32, and the other end bears 25 against a plug 36, projecting from pulley 11. If now a higher speed-gear is suddenly thrown in, the momentary resistance is diffused over a part of the rotation and to an extent equalled by the compression of the yielding spring, 30 which by plug 36 on the pulley is compressed against plug 35 on the disk. (See Fig. 5.) This yielding transition from a lower speed or resistance to a higher one and accompanying compression of the spring is limited by 35 means whereby the driving engagement of pulley 11 to its complementary disk becomes a positive one. This is done by a projection or stop on one of the complementary parts engaging a stop on the other part. For such 40 purpose there is between the plugs a curved rod 37, which occupies the space surrounded by the coils of the spring and the free end of which rod in due time encounters the other plug. After the momentary increase in 45 resistance due to a speed change has been overcome spring 34 may expand again until the plugs rest against each other, as shown in Fig. 4. There is finally a third means to overcome 50 by easy transition the momentarily-created higher resistance due to a change of speeds. This is at the point where operative connection is made between the driven shaft 13 of this device and the part or driving-shaft of the particular apparatus, machine-tool, &c., 55 which by means of this changeable gear-train is driven from shaft 10. This shaft is shown at 38 in the drawings, and the connection for transmitting motion from shaft 13 may be made in two ways.

60 As shown in Fig. 1, transmission by gear-wheel is had, one, 39, being rigidly mounted on shaft 38. The other gear, 41, is carried on a rigidly-mounted sleeve 42 and to which it is held by frictional pressure, thus providing 65 possibility of a limited slippage when excess-

ive resistance due to a speed change exceeds for the moment prevailing driving power, which slippage, however, ceases when this resistance is overcome and after the slower moving machinery has assumed the higher speed. 70 To provide for this frictional engagement of this gear-wheel 41, sleeve 42 is in two parts, each having a flange 43 at its end which project over the sides of the wheel. Suitable friction-promoting material, like leather or 75 fiber, is placed between these flanges and the wheel, and the frictional engagement is adjusted and maintained by means of a nut 44, whereby the flanges of the sleeve, with this material between them, are caused to impinge against the sides of the gear-wheel. In some cases there is no such intermediate shaft 38—that is, no operatively-connected shaft—and shaft 38, on the machine-tool is 80 practically a continuation of driven shaft 13 85 of the speed-gear device. In such case shaft 38 is in line with shaft 13, as shown in Fig. 8, the two being directly connected at their ends. The connection is also one by frictional engagement, permitting a limited slippage 90 and is somewhat similar to the engagement between the complementary parts of a friction-clutch, each part mounted at the end of one of the shafts, with the exception that the parts are not movable to or from each other 95 like in a clutch. In detail this construction is as follows: One shaft carries immovably attached to it a cup 45. Keyed to the other shaft, but free to move longitudinally, is a flanged sleeve 46. Between the two is a washer 100 47, of friction-promoting material, leather or fiber. The two are held to each other with this washer clamped between by a nut 48, which engages the cup and which permits also adjustment of the frictional impingement. 105 This nut does, however, not bear directly against the sleeve, but reaches this latter by means of an interposed follower 49, locked for rotation to cup 45 by means of a key 51 110 and in a manner which does not interfere with the limited movement of nut 48 for adjusting the friction. This cup and nut 48, seated on it, and the follower next to the nut are thus connected so as to move together as a rotary unit, 115 whereby this interposed follower prevents the sleeve locked to shaft 38 and capable of independent movement from acting upon the nut in a way to move the same from its adjusted position by either tightening or loosening the same. An additional washer 52 is interposed between this follower 49 and the flange or sleeve 46 to increase thereby the 120 friction. Of these yielding connections, the one at the initial point, where the power is received, (pulley 11,) and the other at the point where the power is delivered from shaft 13 to shaft 38, one might take the place of the other—that is, the connection yielding by friction on shaft 13 and applied to gear 41 might be applied to the sides of pulley 11 and the 125 130

connection yielding by spring might be applied to gear-wheel 41, or the yielding devices might be alike at both points, either one only being used.

5 It will now be seen that by means of this device constructed as described the speed may be readily and conveniently changed while the parts are in motion without incurring the risk of injury or breakage of teeth when the idler 10 is suddenly thrown into mesh. This is because of the yielding connections shown, which slip and yield when changes are made and at which times the strain and jar incident to such changes is beyond the ordinary driving 15 power of the machinery.

Having described my invention, I claim as new:

1. In a speed-changing device, the combination of a drive and a driven shaft, a series of 20 gear-trains arranged and graduated so that each when in operation transmits to this driven shaft a speed different from the other, an idler, a hand-lever on which it is carried, a rod on which this hand-lever is pivotally 25 mounted and on which it may be laterally adjusted so that the idler on it may engage any of the gear-trains, arms on which this rod is supported at both its ends and on which it may swing transversely to carry the idler to 30 the proper point of engagement and means to lock the hand-lever in the position to which it has been adjusted.

2. In a speed-changing device, the combination of a drive and a driven shaft, a series of 35 gear-trains arranged and graduated so that each when in operation transmits to the driven shaft a speed different from the other, an idler, a pivotally-attached hand-lever on which it is carried and whereby it may be 40 moved to meet for engagement any of the gear-trains, a shelf on which this lever normally rests, a stop on the under side of this lever projecting under the shelf mentioned and adapted to engage the same so as to limit 45 thereby the lift of the lever and means to lock this latter in position after adjustment.

3. In a speed-changing device, the combination of a drive and a driven shaft, a series of gear-trains arranged and graduated so that 50 each when in operation transmits to the driven shaft a speed different from the other, an idler, a pivotally-attached hand-lever on which it is carried and whereby it may be moved to meet for engagement any of the 55 gear-trains, a pin on the under side of this lever and a shelf with openings on which this lever normally rests with its pin occupying one of these openings and from which position the lever cannot be moved to engage the 60 idler with any other train unless this pin is first lifted out of such opening, the arrangement being such, that such lift to permit such movement must be of such extent as to prevent engagement with any gear-train in intermediate or improper position and the le- 65

ver cannot be dropped except the pin on it is above another opening.

4. In a speed-changing device, the combination of a drive and a driven shaft, a series of gear-trains arranged and graduated so that 70 each when in operation transmits to the driven shaft a speed different from the other, an idler, a pivotally-attached hand-lever on which it is carried and whereby it may be moved to meet for engagement any of the 75 gear-trains, a shelf on which this lever normally rests, a series of openings provided in this shelf, a pin projecting from the under side of the lever, preventing by its contact with the shelf engagement of the idler with 80 a gear-train when in improper position except said pin occupies one of the openings mentioned and means to lock the hand-lever in its adjusted position.

5. In a speed-changing device, the combination of a drive and a driven shaft, a series of 85 gear-trains arranged and graduated so that each when in operation transmits to the driven shaft a speed different from the other, an idler, a pivotally-attached hand-lever on 90 which it is carried and whereby it may be moved to meet for engagement any of the gear-trains, a shelf on which this lever normally rests, a series of openings provided in this shelf, and a spring-actuated locking-bolt 95 carried on this hand-lever and adapted to lock it in position by occupying one of these openings.

6. In a speed-changing device, the combination of a drive and a driven shaft, a series of 100 gear-trains arranged and graduated so that each when in operation transmits to the driven shaft a speed different from the other, an idler, a pivotally-attached hand-lever on which it is carried and whereby it may be 105 moved to meet for engagement any of the gear-trains, a shelf on which this lever normally rests and which is provided with openings, a series on its upper side and a series in its front side, a pin projecting from the 110 under side of the lever, preventing by its contact with the shelf, engagement of the idler with a gear-train, except said pin occupies one of these openings in the upper side of the shelf and a spring-actuated locking-bolt, 115 also carried on this hand-lever and adapted to enter one of the openings in the front side only when entrance of the pin in one of the other openings has permitted the hand-lever to drop in proper position.

7. In a speed-changing device, the combination of a drive and a driven shaft, a series of gear-trains, arranged and graduated so that 120 each when in operation transmits to the driven shaft a speed different from the other, an idler, a hand-lever on which it is mounted, a movable pivot on which this hand-lever is supported so that the idler is free to be carried laterally to any gear-train for engaging the same, means to guide the hand-lever during 125 130

this lateral movement so that it is confined to move in a line above the points at which meshing contact may take place and a locking device to hold it in its adjusted position.

- 5 8. In a speed-changing device, the combination of two parallel shafts, graduated gears arranged in sets mounted on them, an idler, a hand-lever on which it is carried, a movably-supported rod arranged parallel to the shaft 10 on which the hand-lever is pivoted and whereby the hand-lever is permitted to carry the idler to a position to meet any gear set, a shelf on which this lever normally rests, a groove in this shelf arranged at an angle to the shafts 15 mentioned and a projection on the hand-lever which occupies this groove and serves as a means to guide this lever during its manipulation to proper meshing contact in a horizontal plane.
- 20 9. In a speed-changing device, the combination of a drive and a driven shaft, gear-wheels on each rigidly mounted opposite each other and arranged to form sets graduated for speed, an adjustable idler whereby by its engagement 25 with any of the gear sets variable speeds may be transmitted to the driven shaft, an additional set of gear-wheels proportioned to transmit to the driven shaft a speed slower than any of the others and a permanently-located idler which constantly operates this set, 30

one only of the wheels of this set being rigidly mounted, while the other is mounted for rotation in one direction only, so that the driven shaft may at any time assume a faster speed in the same direction.

10. In a speed-changing device, the combination of a drive and a driven shaft, gear-wheels on each rigidly mounted opposite each other and arranged to form sets graduated for speed, an adjustable idler whereby by its engagement 35 with any of the gear sets variable speeds may be transmitted to the driven shaft, an additional set of gear-wheels proportioned to transmit to the driven shaft a speed slower than any of the others, one being rigidly 40 mounted and the other provided with a recess in its side, a rigidly-mounted ratchet-wheel occupying this recess, pawls whereby this latter gear-wheel acts upon the ratchet-wheel in a manner to rotate its shaft and a permanently-located idler which constantly operates this 45 set in a manner permitting the driven shaft to assume at any time the faster speed as transmitted by any of the other gear sets.

In testimony whereof I hereunto set my signature in the presence of two witnesses.

HENRY DRESES.
